(57) **CLAIM**

The ornamental design for a combined hanger and ice scraper, as shown and described.

DESCRIPTION

A portion of the disclosure of this patent document contains material which is subject to copyright and trademark protection. This patent document shows the copyrighted logo depicting a cloud and snowflake and the trademark snow scraper owned by the Applicant. The Applicant has no objection to the facsimile reproduction by anyone of the patent disclosure as it appears in the Patent and Trademark Office patent files or records, but otherwise reserves all copyright and trademark rights whatsoever.

FIG. 1 is a front view of a combined hanger and ice scraper showing my new design;

FIG. 2 is a front and bottom perspective view thereof;

FIG. 3 is a front view thereof, shown in an environment of use;

FIG. 4 is a front perspective view thereof;

FIG. 5 is a perspective, sectional view of the combined hanger and ice scraper taken in the direction of line 5-5 of FIG. 1; and,

FIG. 6 is a ride side view thereof.

The broken lines in the drawings depict environmental structure and forms no part of the claimed design.

1 Claim, 3 Drawing Sheets
